UNITED STATES PATENT OFFICE.

JOHN C. ERNST, OF ANSONIA, CONNECTICUT, ASSIGNOR OF ONE-HALF TO
RUDOLPH N. JOHNQUEST, OF SAME PLACE.

FINGER-NAIL CLIPPER.

SPECIFICATION forming part of Letters Patent No. 671,793, dated April 9, 1901.

Application filed February 12, 1901. Serial No. 46,971. (No model.)

To all whom it may concern:

Be it known that I, JOHN C. ERNST, a citizen of the United States, residing at Ansonia, county of New Haven, State of Connecticut, have invented certain new and useful Improvements in Finger-Nail Clippers, of which the following is a specification.

My invention relates to the class of finger-nail clippers in which curved cutting-jaws normally separated by spring action are moved toward each other, as in the act of clipping a nail, by an operating-lever; and my invention has for its objects to simplify and cheapen the construction, so that the cost of production can be appreciably reduced, to greatly improve their operation in use, to provide a simple and convenient locking device that will retain the cutting-jaws in the closed position and the operating-lever wholly out of the way, and, furthermore, to render the device less bulky and cumbersome and more attractive in general appearance than any device of the character that has heretofore been placed upon the market.

With these ends in view I have devised the simple and novel nail-clipper of which the following description, in connection with the accompanying drawings, is a specification, reference characters being used to designate the several parts.

Figure 1 is a plan view of my novel nail-clipper in the closed position; Fig. 2, an inverted plan view; Fig. 3, an edge view, also in the closed position; Fig. 4, a longitudinal section in the open position, these views all being natural size; Fig. 5, a detail view, partly in horizontal section, on an enlarged scale, illustrating the means for locking the operating-lever in its closed or out-of-the-way position, as in Figs. 1 and 3; and Fig. 6 is a detail perspective showing the operating-lever and the connecting-piece detached, the lower member being in horizontal section.

The body of my novel clipper consists of two members 20 and 21, which for convenience I will term the "upper" and "lower" members, respectively. This body may be made from one piece of spring metal or of two pieces rigidly secured together, as may

be preferred, and either member or both members may be spring members. Ordinarily, however, member 20 will be made relatively rigid and member 21 sufficiently resilient to throw the cutters or cutting-jaws 22, carried by the free ends of the members, to the open position.

23 denotes the operating-lever, which is pivoted in a slot 24 in the upper member. The slot and the operating-lever are so shaped relatively to each other that in the closed position the operating-lever will lie wholly in the slot and flush with the top surface of the upper member. The operating-lever is provided in its forward end with a vertical longitudinal slot 25 and in its upper side with a transverse groove 26, which intersects the rear end of the slot, as clearly shown in Fig. 6. The operating-lever is secured in place by means of a pivot-pin 27, which is shown as passing transversely through the operating-lever and transversely through the upper member on opposite sides of slot 25. The operating-lever is connected to the lower member by means of a detachable connecting-piece 28. This connecting-piece is in shape a double T—that is to say, two parallel end pieces *a* are connected by a central strip *b*, lying at right angles to the end pieces. Near the forward end of member 21 is a longitudinal slot 29, and lying transversely to the mid-length of this slot on the outer side of the member is a groove 30, which is adapted to just receive one of the end pieces *a* of connecting-piece 28, as clearly shown. In assembling connecting-piece 28 is passed upward through slot 29, and when the upper cross-piece *a* has passed through said slot the connecting-piece is given a quarter-turn and the lower end piece *a* is caused to lie in the transverse groove 30. The operating-lever may then be engaged with the upper arm of the connecting-piece, the operating-lever being inserted in approximately the position shown in Fig. 4, the central strip *b* of connecting-piece 28 passing into vertical slot 25 in the operating-lever and the upper end piece *a* engaging transverse groove 26 in the operating-lever, as will be understood from Fig. 4 in connection with Fig. 6. It will be

noted from Fig. 4 that the resistance-arm of the operating-lever is relatively short and that in use power is applied directly to raise the lower member to the closed position, so that there is no loss of power.

5 31 denotes a file, which I preferably provide on the outer side of member 21.

As a means for retaining the operating-lever in the closing position I provide a loose 10 disk 32 in a housing 33, which is adapted to engage the lower end of the operating-lever by gravity only. I have shown the lower end 15 of the operating-lever as provided with an overhanging boss or projection 34, which also serves as a finger-piece. The locking-disk is provided with a central opening 35, and the housing is retained in position by a central 20 rivet 36, which passes through the opening in the disk, as is clearly shown in Fig. 5, in which the top of the housing and a portion 25 of the overhanging boss are removed, rivet 36 being in section. In this figure the locking-disk is shown in full lines in the unlocking position and in dotted lines in the locking position. The operation of locking and 30 unlocking the operating-lever is by gravity alone. The operator simply presses the operating-lever down into slot 24, and if he desires to lock it there holds the implement 35 with the housing end upward. As soon as the implement is placed in this position the locking-disk will drop by gravity to the relative position indicated by dotted lines in Fig. 5, which will place the edge of the locking-disk under the edge of the overhanging boss, so that the instant the operator relieves the 40 pressure upon the operating-lever the resiliency of the lower member or of both members, as may be, which will be exerted to move the jaws toward the open position, will lock the lever in the closed position through frictional contact of the locking-disk with the housing and the overhanging boss. The parts 45 will remain securely locked in this position and the implement may be handled to an almost unlimited extent without disengagement of the operating-lever. To disengage the operating-lever is equally simple. The operator merely holds the implement with 50 the housing end downward and presses inward upon the overhanging boss. This relieves the spring-pressure of the operating-lever upon the locking-disk, so that the latter will drop downward in the housing to the 55 relative position shown in full lines in Fig. 5 and release the operating-lever. The implement may or may not be provided with a ring 37 for attachment to a watch-chain or any similar use.

60 Having thus described my invention, I claim--

1. A finger-nail clipper comprising members provided with cutting-jaws, one of said members having a connecting-piece with a central strip and an end piece and the other member having a pivoted operating-lever with

a slot at its forward end which receives the central piece of the connecting-strip and a groove which receives the end piece.

2. A finger-nail clipper comprising members 70 provided with cutting-jaws, one of said members having a connecting-piece with a central strip and an end piece and the other member having a pivoted operating-lever engaging the connecting-piece, the free end of 75 said operating-lever having an overhanging boss, and a gravity-disk upon the member adapted to lock the operating-lever in the closing position.

3. In an implement of the character described 80 the combination with a member 21 having a vertical longitudinal slot near one end thereof and a groove in its outer side transverse to the slot and a member 20, of a connecting-piece consisting of two end pieces 85 and a central strip, said parts being assembled by passing one end piece through the slot, then giving the connecting-piece a quarter-turn and placing the other end piece in the groove, and a pivoted operating-lever carried by member 20 and having at its forward end a slot to receive the central strip and a groove to receive the end piece.

4. In an implement of the character described 95 the combination with members having cutting-jaws which normally remain apart, of an operating-lever pivoted to one member and engaging the other member, whereby said members may be moved to the closed position, said operating-lever having an overhanging boss, and a gravity locking-disk upon the member to which the lever is pivoted 100 which is adapted to engage the boss to lock the lever in the closing position.

5. In an implement of the character described 105 the combination with members having cutting-jaws which normally remain apart, one of said members having a housing, of an operating-lever provided with an overhanging boss and pivoted to one member and engaging the other member, and a loose disk 110 within the housing which is adapted when the lever is pressed inward to lock or release said lever by gravity.

6. In an implement of the character described 115 the combination with members having cutting-jaws which normally remain apart, of an operating-lever provided with an overhanging boss and pivoted to one member and engaging the other member, a housing upon 120 the member to which the lever is pivoted, a central rivet by which the housing is secured in place and a locking-disk within the housing having a central opening through which the rivet passes loosely, said disk being adapted 125 to engage the overhanging boss by gravity.

7. A finger-nail clipper comprising members provided with cutting-jaws which normally remain apart, one of said members having a connecting-piece with a central strip 130 and an end piece and the other member having a pivoted operating-lever with a slot at its

forward end to receive the central piece and a groove which receives the end piece and means for locking the operating-lever in the closing position.

5 8. A finger-nail clipper comprising members provided with cutting-jaws which normally remain apart, an operating-lever pivoted to one member and engaging the other member and a gravity-disk carried by the

member to which the lever is pivoted and to which is adapted to lock the lever at either the open or closing position.

In testimony whereof I affix my signature in presence of two witnesses.

JOHN C. ERNST.
